UNITED STATES PATENT OFFICE.

JOSEPH W. PHINNEY, OF MEDFORD, MASSACHUSETTS, ASSIGNOR TO THE AMERICAN TYPE FOUNDERS' COMPANY, OF NEW YORK, N. Y., A CORPORATION OF NEW JERSEY.

DESIGN FOR A FONT OF TYPE.

SPECIFICATION forming part of Design No. 35,839, dated April 1, 1902.

Application filed February 3, 1902. Serial No. 92,357. Term of patent 14 years.

To all whom it may concern:

Be it known that I, JOSEPH W. PHINNEY, of Medford, in the county of Middlesex and State of Massachusetts, have invented and 5 produced a new and original Design for a Font of Type, of which the following is a specification.

This design consists of capital and small letters and a set of Arabic numerals, the capital and small letters being of the so-called "Old English" style.

The general characteristic of the capital letters, with the exception of the C, G, O, Q, and T, is their rectangular appearance—that 15 is, the letters do not appear to differ materially in width the one from the other, (except the M and W, which are slightly wider than the others,) and the upper part of each letter, except the letter A, is of substantially 20 the same width as the base. The base and top lines, whether single or compound, (for example, the top of the letters E and F,) while they are ogee in shape, have but a slight curve, which fact adds to the general straightness 25 and squareness of the letter. The serifs or base-lines of almost all these letters start upon the left at a point and broaden materially, ending in a line at an acute angle to the base, and so with the top lines of the letters E, H, 30 L, and S. The top serifs of the letters K and N have the reverse shape. The capitals X and Z each have a horizontal cross-mark of considerable width. The H has a fine wavy descending line.

35 The whole effect produced is that of a font the individual capitals of which are strong and compact and yet graceful without any unnecessary curve of line, just sufficient curve being given to the ogee lines to take away 40 that stiffness which would exist if the lines were straight, and this effect is produced rather more by the form of taper given to the ends of the ogee lines than by the shape of the lines themselves. Moreover, these ogee lines 45 are so closely joined to the other parts of the letters that a notched effect is avoided, this assisting in the rectangular effect above spoken of.

The small letters have very much the same clear-cut symmetrical appearance of the capitals. The ascending portion of the letter d is at an angle of about forty-five degrees with the vertical. The small h and small j have wavy descending portions and the small v and small w wavy ascending portions, these 50 ascending and descending portions tapering to a point. The end of the ascending portion of b, d, h, k, l, and t is pointed and curved rearwardly and downwardly, as is also the end of the descending portion of q. The end 55 of the descending portion of p is also pointed, but curved forwardly.

The numerals are quite irregular in character. The serifs at the bottom of the numerals 1 and 4 and the bottoms of numerals 2, 3, 5, 6, 8, 9, 0 all have the characteristic form of the serifs of the capital letters—that is, they start at a point and broaden to the end with rather an abrupt increase in width. The upper portions of the numerals 2 and 3 are 65 of the same character, except that they curve upward instead of downward. The vertical portion of the numeral 3 consists of two broad lines, the opposing ends of which are connected by substantially horizontal curved fine 70 lines, the characteristic middle cross-lines of the numeral 8 being formed of similar fine lines joining the upper and lower ends of similar broad lines.

The whole effect of this font is that of a 75 clear sharply-cut engraved letter, this effect being produced somewhat by the sharp contrast between the width of the broad lines and the sharpness, strength, and yet narrowness of the fine lines.

80 What I claim as my invention is—

The design for a font of type as herein shown and described.

In testimony whereof I hereunto set my name this 21st day of January, 1902.

JOSEPH W. PHINNEY.
